A. B. Reavis
ATTORNEY

UNITED STATES PATENT OFFICE.

NEIL E. SALSICH, OF BETHLEHEM, PENNSYLVANIA.

FOOT GUARD.

Application filed July 17, 1923. Serial No. 652,040.

To all whom it may concern:

Be it known that I, NEIL E. SALSICH, a citizen of the United States, and residing at Bethlehem, Lehigh County, State of Pennsylvania, have invented certain new and useful Improvements in Foot Guards, of which the following is a specification.

My invention relates to foot guards for use in connection with guard rails or in connection with railroad rails of any type which define divergent spaces which are a source of danger owing to the likelihood of one getting his foot caught in such space, and it has for its object to provide apparatus of the character designated which shall be capable of being readily rolled and which shall be of such a construction as to be susceptible of being readily shaped to fit divergent spaces of this character.

20 A further object of my invention is to provide a guard construction which will not only serve as a safety device, as pointed out, but which will limit the accumulation of snow and ice or other material between the 25 guard and main rails and permit of ready cleaning out of the space between the rails.

Apparatus made in accordance with my invention is illustrated on the accompanying drawings, forming a part of this application, in which—

30 Figure 1 is a plan view of a main and guard rail showing one form of my improved foot guard;

Figure 2 is a section taken along the line 35 II—II of Figure 1 and viewed in the direction of the arrow;

Figures 3 and 4 are perspective views of a 40 foot guard intended for use where the guard and main rails are parallel;

Figure 5 is a perspective view of a foot 45 guard having a trapezoidal top to fit divergent spaces between bent ends of a guard rail and a main rail;

Figure 5^a is a fragmentary plan view 50 showing a guard rail of the bent-end type with the form of foot guard shown in Figure 5 in place;

Figure 6 is a plan view showing a further modified type of guard;

55 Figure 7 is a view on a larger scale of one of the guard sections employed in Figure 6; and

Figure 8 is a sectional view taken along the line VIII—VIII and viewed in the direction of the arrow.

55

Referring now to the drawings for a better understanding of my invention, in Figure 1, I show a main or track rail 10 and a guard rail 11, the latter rail having a web portion 12 which is substantially parallel throughout 60 its length to the web portion 13 of the main rail 10. The head portion 14 of the guard rail is machined off at its ends as indicated at 15 in order to provide widened entrance spaces for wheel flanges.

65

In order to avoid the divergent entrance spaces of the character just referred to being a source of danger, I provide foot guards 17 of box-like form to fill the space between the webs of the guard and main 70 rails sufficiently to prevent one from having his foot caught therein. The foot guard is preferably secured to the web portion 12 of the guard rail in any suitable manner, as by means of the rivets 18.

75

The foot guard is illustrated more in detail in Figures 3 and 4, from which it will be seen that the guard is in the form of an angle section having a lateral flange 19 for attachment to a rail web portion and a top 80 flange 20 for blocking a divergent end space. The flange 20 is extended beyond the flange 19 at one end to provide a lip 21, which, when bent down, effectively blocks in an end-wise direction the space between rails.

85

In Figures 1, 2, 3 and 4, I show a form of foot guard in which the width of the top flange 20 is substantially uniform from end to end. This type of construction is suitable where the main rail and the guard rail 90 web portions are substantially parallel throughout the length of the guard rail. However, in case the web portion of the guard rail diverges from the web portion of the track rail, it is necessary that the top portion of the foot guard shall be modified to fit the divergent space. This may be readily done with my type of foot guard merely by machining one edge, thereby producing a foot guard having a substantially trapezoidal top portion 20' to fit between 95 the rails, as shown in Figure 5^a.

In Figures 6, 7 and 8, I show a further modified form of foot guard which is co-

extensive with the guard rail. In these views, I show main and guard rails 10 and 11 having parallel webs 13 and 12, respectively, and a guard member construction 17' co-extensive with the guard rail 11. To facilitate manufacture and installation the guard structure 17' is preferably made in a plurality of sections 23, one of which is shown on larger scale in Figure 7.

Each section 23 is preferably made from rolled angle bar and consists of a lateral wall 19', provided with a suitable number of openings 24 to receive rivets 25, whereby the foot guard is secured to the web 13 of the guard rail 11, and a top wall 20'', which serves to obstruct the space between the main rail and the guard rail throughout the length of the latter. Each section 23 has its top portion extending beyond the side portion 19' at each end of the latter to provide lip portions 21', which, when bent down as shown on the drawings, effectively block the spaces between the main rail and the guard rail at the ends of the latter. In addition to the obstructive function of the lip members 21', these members also serve to brace the guard structure; and in this connection, as may be seen from Fig. 8, where the lip 21' is shown as being provided with an edge 39 conforming to the inclination of the top surface of a rail flange and being arranged closely contiguous to the latter, that due to this construction, the foot guard constitutes an effective hold-down to restrain outward 35 tilting of the main rail from the guard rail. Also, conversely, the foot guards limit possible tilting of a guard rail toward the main rail.

As may be seen from Figs. 1 and 4, the rivet openings for the foot guard are arranged near to the outer end of the latter, or the end having the downwardly-extending lip 21', with result that, if the foot guard is called upon to serve as a hold-down to restrain outward tilting of the main rail, the rivets serve to the best advantage in resisting shearing stresses,—the nearer the rivets are to the point of application of the applied force, the less the shearing moments.

In addition to the members 23 serving to block the space between the rails near the top and at the ends, the structure also limits the accumulation of snow and ice or other material between the main rail and the guard rails and makes it easy to clean out the space between the rails.

While I have shown my invention in three forms, it will be obvious to those skilled in the art that it is not so limited, but is susceptible of various other changes and modifications without departing from the spirit thereof, and I desire, therefore, that only such limitations shall be placed thereupon as are imposed by the prior art or as are specifically set forth in the appended claims.

Having thus described the invention what is claimed as new and desired to be secured by Letters Patent is:

1. The combination, with a main rail and a guard rail having parallel webs and the guard rail having a head portion which is cut away on a taper at the ends and at the main rail side to provide converging wheel-flange entrance spaces, of foot guard structures for the entrance spaces each of which includes a vertical flange secured to the web of the guard rail, a top flange integral with the upper edge of the vertical flange and having its opposite edge arranged beneath and overlapped by the head of the main rail, and an end flange or lip integral with the outer end of the top flange and extending downwardly to block the space below the top flange and between the rails.

2. The combination, with a main rail and a guard rail having parallel webs and the guard rail having a head portion which is cut away on a taper at the ends and at the main rail side to provide converging wheel-flange entrance spaces, of foot guard structures for the entrance spaces each of which includes a vertical flange secured to the web of the guard rail, a top flange integral with the upper edge of the vertical flange and having its opposite edge arranged beneath and overlapped by the head of the main rail, and an end flange or lip integral with the outer end of the top flange and having a portion of its lower edge inclined to conform to the inclination of the top surface of a main rail flange, said inclined portion of the lower edge being arranged contiguously to the upper surface of a main rail flange.

3. The combination, with a main rail and a guard rail having parallel webs and the guard rail having a head portion which is cut away on a taper at the ends and at the main rail side to provide converging wheel-flange entrance spaces, of foot guard structures for the entrance spaces each of which includes a vertical flange, a top flange integral with the upper edge of the vertical flange and having its lateral edge opposite to the vertical flange arranged beneath and overlapped by the head, a downwardly-extending lip or flange integral with the top flange and having a bottom edge arranged over and contiguous to the top surface of a main rail flange, and rivet means for securing the vertical flange to the guard rail web arranged near to the end of such flange which is adjacent to the downwardly-extending lip or flange.

4. The combination, with a guard rail structure including supporting means and a head portion joined by a web which is straight from end to end and the head portion being cut away on a taper at the ends and at the main rail side thereof, of foot

guard structures for the ends of the guard rail each of which includes a vertical flange secured to the web of the guard rail, a top flange integral with the upper edge of the 5 vertical flange and being of substantially uniform width from end to end, and a downwardly-extending flange integral with the outer end of the top flange and having the

portion of its bottom edge adapted to adjoin a main rail flange inclined upwardly so 10 as to be contiguous to the top surface of a main rail flange when the structure is installed.

In testimony whereof I hereunto affix my signature this 5th day of July, 1923.

NEIL E. SALSICH.
